(57) **CLAIM**

The ornamental design for smartglasses temples, as shown and described.

DESCRIPTION

FIG. 1 is a front top perspective view of smartglasses temples showing our new design;

FIG. 2 is a front view thereof;

FIG. 3 is a rear view thereof;

FIG. 4 is a top view thereof;

FIG. 5 is a bottom view thereof;

FIG. 6 is a left side view thereof, which is a mirror image of a right side view thereof; and,

FIG. 7 is an inside elevational view of the right temple, which is a mirror image of an inside elevational view of the left temple.

The broken lines in the drawings are for the purpose of illustrating unclaimed portions of the smartglasses temples and form no part of the claimed design.

The smartglasses temple is shown separately in FIG. 7 for ease of illustration only.
